UNITED STATES PATENT OFFICE

ARNOLD SCHWARZ, OF PRAGUE, CZECHOSLOVAKIA

DESIGN FOR A CELLULOID COVER FOR A MOUTH-HARMONICA

Application filed February 14, 1931, Serial No. 38,662, and in Czechoslovakia November 9, 1930.
Term of patent 14 years.

To all whom it may concern:

Be it known that I, ARNOLD SCHWARZ, a citizen of the Republic of Czechoslovakia, residing at Prague, in Czechoslovakia, have invented a new, original, and ornamental Design for a Celluloid Cover for a Mouth-Harmonica, of which the following is a specification, reference being had to the accompanying drawings, forming part thereof.

I claim:

The ornamental design for a celluloid cover for a mouth-harmonica as shown.

ARNOLD SCHWARZ.
